UNITED STATES PATENT OFFICE.

SUTTON STRONG, OF HARMONY, INDIANA.

TRANSOM-OPERATOR.

SPECIFICATION forming part of Letters Patent No. 312,224, dated February 10, 1885.

Application filed May 14, 1884. (No model.)

To all whom it may concern:

Be it known that I, SUTTON STRONG, a citizen of the United States, and a resident of Harmony, in the county of Clay and State of Indiana, have invented certain new and useful 5 Improvements in Revolving Sashes or Transom-Locks; and I do hereby declare that the following is a full, clear, and exact description of the invention, which will enable others 10 skilled in the art to which it appertains to make and use the same, reference being had to the accompanying drawings, which form a part of this specification, and in which—

Figure 1 is a view of a portion of a door-jamb and of a transom-sash provided with my 15 improved lock, showing the lock in edge view. Fig. 2 is a view of the lock detached. Fig. 3 is a view of the portion of the lock secured to the sash. Fig. 4 is a view of the portion 20 of the lock secured to the jamb, and Fig. 5 is a view of the locking-lever.

Similar letters of reference indicate corresponding parts in all the figures.

My invention has relation to locks for adjusting sashes in transoms or similar tilting windows; and it consists in the improved construction and combination of parts of the same, as hereinafter more fully described and claimed.

30 In the accompanying drawings, the letter A indicates the door-jamb, and B the sash, and a plate, C, having a straight edge, D, a projecting lug or pin, E, and a segmental edge, F, concentric with the pin, is secured upon the side of the door-jamb, flush with the surface of the same, forming a segmental groove or recess, G, inside the segmental edge, the inner side of which groove or recess forms a segmental cogged rack, H.

40 A casing, I, of the same shape and size as the plate, is secured to the sash, and is provided with a flange, J, at its edges, which bears against the face of the plate upon the jamb, and the casing has a curved slot, K, opening from the straight edge of the same, the inner end of which slot forms a bearing, L, concentric with the segmental edge of the casing, adapted to receive and form a rocking bearing for the lug upon the plate upon the 45 jamb. The flange of the casing is cut away near one end of the segmental edge of the casing, as shown at M, and two lugs, N, project from the

edge to the same height as the flange—a distance from each other—and the plate has a V-shaped slot inside these lugs, the point of 55 the slot pointing toward the central bearing of the casing. Two lugs, O O, project from the inner open side of the casing at the ends of the V-shaped slot, between the same and the central bearing, and two pairs of lugs, P P, 60 project from the inner open side of the casing, one pair in the corner of the casing between the V-shaped slot and the straight edge of the casing, and the other pair of lugs near the end of the segmental edge of the casing, and two 65 springs, Q Q, are held at their inner ends between these two pairs of lugs, projecting with their free ends over the ends of the V-shaped slot, and bearing against the lugs at the ends of the said slot.

70 R is the locking-lever, which consists of an outer handle, S, a middle portion, T, having two curved slots, U U, sliding upon the lugs at the edge of the casing, and provided with a laterally-projecting lug or tooth, V, which 75 engages the segmental rack of the plate upon the jamb, and an inner heart-shaped end, W, provided with a lug, X, which projects into the V-shaped slot and rocks in the same. The springs in the casing bear with their free ends 80 in the shoulders formed by the heart-shaped inner end of the locking-lever, forcing it back into the position in which the lug upon its inner end is in the point of the V-shaped slot, when the lug upon its middle will be engaged 85 between two of the cogs of the segmental rack upon the plate upon the jamb. It will now be seen that when the plate upon the jamb is secured in its place and the plate for the sash is secured in the edge of the sash the curved 90 slot of the latter plate or casing may be slid upon the lug upon the plate upon the jamb, when the tooth or lug upon the middle of the locking-lever will engage the segmental rack, holding the plates in their relative positions, 95 the said lug or tooth sliding in the groove outside the segmental rack.

When it is desired to tilt the transom, the locking-lever may be either tilted upward or downward, depending upon the side to which 100 it is desired to tilt the transom, the lever and transom being tilted to the same side, when the lug upon the lever will be disengaged from the rack upon the jamb, and the transom may

now be drawn or pushed by the lever until in its desired position, when the lever is released, and when the springs in the casing will force the lever into its normal position, 5 with its inner lug in the apex of the V-shaped slot, and with its lug or tooth engaging the rack.

Having thus described my invention, I claim and desire to secure by Letters Patent of the 10 United States—

The combination of the jamb-plate formed with a segmental grooved edge, a cogged rack inside the said groove, and a lug or pin concentric with the said edge and rack, the flanged 15 sash-casing shaped similarly to the jamb-plate, formed with the curved slot and bearing, the V-shaped slot, the lugs at its segmental edge, and the spring-holding lugs, all as de-

scribed, the springs held at their inner ends by the spring-holding lugs, and the locking- 20 lever consisting of the handle, the central portion having the curved slots rocking upon the lugs at the edge of the casing, and having the rack-engaging lug, and the inner heart-shaped end provided with the lug sliding in the V- 25 shaped slot, and having the springs bearing against the shoulders formed by it, as and for the purpose shown and set forth.

In testimony that I claim the foregoing as my own I have hereunto affixed my signature 30 in presence of two witnesses.

SUTTON STRONG.
